UNITED STATES PATENT OFFICE

HENRY T. TRAUTVETTER, OF CLIFTON, NEW JERSEY

DISPENSING CONTAINER

Application filed August 2, 1928. Serial No. 298,977.

This invention relates to dispensing containers which are especially designed for holding and dispensing condiments, such as sugar, salt, pepper or the like.

Containers for substances of this character which are now in general use are open to the objection that moisture gains access to the contents and seriously interferes with the dispensing of the same. In addition to this, 10 said containers, unless provided with a cover, admit dust, dirt and insects which render the contents unsanitary.

The present invention broadly comprehends a dispensing container which is positively sealed against the entrance of moisture, 15 dust, dirt or insects by the mere act of resting or placing the same upon a supporting surface, due to the fact that the same is provided with an outlet through the lower end while 20 the upper end is completely closed.

More specifically, the invention contemplates an improved dispensing container having a completely closed upper end and a bottom wall having an upwardly projecting outlet tube opening through said bottom wall and terminating in closely spaced relation to the closed top wall so as to render the same 25 moisture proof, dust proof, as well as insect proof, when the same is supported by resting 30 the bottom wall on a supporting surface.

The invention furthermore embodies a dispensing container of the character set forth which may be constructed with a reduced extension at the upper end in alignment with 35 the outlet tube for receiving a predetermined measured quantity of the contents when the same is inverted so that successive inversions and rightings of the container will dispense substantially uniform quantities of the contents.

The invention aims to further provide a dispensing container of the character set forth which when employed for containing 45 salt may dispense the same by rapid upward jerks to cause the contents to move upward against the top wall and for deflection thereby through the outlet tube.

Other features reside in the simplicity of 50 construction of the container, the economy

with which it may be produced and the general efficiency derived therefrom.

With the above recited and other objects in view, reference is had to the following description and accompanying drawings, in 55 which there is exhibited one example or embodiment of the invention, while the claims define the actual scope of the same.

In the drawings:

Figure 1 is a vertical sectional view of a 60 dispensing container constructed in accordance with the invention, and particularly designed for dispensing measured quantities of the contents.

Figure 2 is a similar view illustrating the 65 container inverted.

Figure 3 is a plan view of the sealing ring or gasket for binding or impinging the bottom wall against the lower open end of the body.

Figure 4 is an edge view of said sealing ring or gasket.

Figure 5 is a vertical sectional view through a dispensing container illustrating a modified adaptation of the invention.

Figure 6 is a perspective view thereof illustrating the manner in which the same is used for dispensing the contents.

Referring to the drawings by characters of reference, and more particularly to the form of the invention illustrated in Figures 1 and 2, 10 designates the body of the container which is of inverted cup shaped configuration having a closed upper end 11 provided with an upwardly projecting reduced extension 12 defining a pocket 13 of reduced diameter with respect to the main body 10. The lower end of the body 10 is provided with external threads 14 and with an internal frusto-conical seat 15. A dome shaped bottom wall 16 including a frusto-conical marginal flange 17 depending therefrom and designed to snugly fit within the frusto-conical seat 15, is provided, and said flange 17 is formed with an out-turned bead 18. A retaining ring or annulus 19 is threaded over the external threads 14 and is provided with an inturned annular lip 20. A binding element or gasket 21 of annular or ring form having circumferentially spaced radial off-

sets 22, is designed to be interposed between the bead 18 and the lip 20 for effecting a close seating of the flange 17 of the bottom wall against the seat 15. The bottom wall 16 is provided with a concentric upwardly projecting outlet tube 23 which opens through the bottom wall and which extends upwardly to a point closely spaced from the top wall 11 adjacent its juncture with the extension 12. In order to properly retain the outlet tube 23 in a centered position, the same is castellated or provided with a spider 24. It will be observed that the internal diameter of the outlet tube 23 is slightly less than the internal diameter of the extension 12 or the pocket 13 which it defines.

In practice, the bottom wall is removed by unthreading the retaining ring 19 and introducing the contents to the body while the same is in an inverted condition. After the bottom wall has been applied, the contents are dispensed in predetermined measured quantities by successively inverting and righting the container. It is obvious from the showing in Figure 2 that a predetermined quantity of the contents will gravitate into the pocket 13 when the container is inverted, and obviously, when the same is righted or moved back to its normal position, that the greater part of the contents trapped in the pocket 13 will flow outwardly through the tube 23. When not in active use, the container is obviously rested upon a supporting surface S which seals the same against the entrance of insects, dust, dirt or dampness. It is, therefore, apparent that no cover is necessary, and hence the user is not subjected to the inconvenience of opening or removing a cover and replacing the same every time the container is used.

In the form of the invention illustrated in Figure 5, the construction is substantially identical with that of the preferred embodiment except that the top wall indicated at 11^a terminates in a rounded dome 12^a. This renders the container especially adaptable for use as a salt shaker in that the contents are dispensed by merely jerking the container rapidly up and down to cause the contents to be deflected by the upper dome shaped portion or apex 12^a of the top wall 11^a, thence through the outlet tube 23.

What is claimed is:

1. A dispensing container comprising an inverted cup shaped body having a completely closed non-supporting upper end and a lower open supporting end, a removable closure for said lower end having an outlet opening and an upstanding open ended tube extending from said outlet opening to a point adjacent to and spaced from the upper end of said body.

2. A dispensing container comprising an inverted cup shaped body having a completely closed non-supporting upper end and a

lower open supporting end, a removable closure for said lower end having an outlet opening and an upstanding open ended tube extending from said outlet opening to a point adjacent to and spaced from the upper end of said body, the upper end of said body being provided with an upwardly projecting reduced extension defining a pocket for receiving, measuring and dispensing a quantity of the contents upon inversion of the container and the return of the same to a normal position.

3. A dispensing container including an inverted cup shaped body having an upwardly projecting pocket formed with a downwardly and outwardly flared mouth and a bottom wall having an upwardly projecting outlet tube opening through the bottom wall and terminating in closely spaced relation to the closed top wall of the body, said outlet tube having a castellated upper end for engagement with the flared mouth of the pocket to center and properly space the same therefrom.
